(57) **CLAIM**

The ornamental design for a tire as shown and described.

DESCRIPTION

FIG. 1 is a side perspective view of a first embodiment of a tire showing our new design, it being understood that the tread pattern is repeated throughout the circumference of the tire, the opposite side being the same as that shown; FIG. 2 is a front elevational view of the first embodiment of the tire;

FIG. 3 is a side elevational view of the left side of the first embodiment of the tire;

FIG. 4 is a side elevational view of the right side of the first embodiment of the tire; and,

FIG. 5 is an enlarged fragmentary view of FIG. 2.

The broken lines in various embodiments defining the tread blocks, shoulder blocks, sidewall, and inner bead depict environmental subject matter that forms no part of the claimed design.
